(57) **CLAIM**

The ornamental design for an alignment tool, as shown and described.

DESCRIPTION

FIG. 1 is a perspective view of the alignment tool;

FIG. 2 is a top plan view thereof;

FIG. 3 is a bottom plan view thereof;

FIG. 4 is a right side elevation view thereof;

FIG. 5 is a left side elevation view thereof;

FIG. 6 is a front elevation view thereof; and,

FIG. 7 is a rear elevation view thereof.

The broken lines are for illustrative purposes only and form no part of the claimed invention.
